UNITED STATES PATENT OFFICE

FRANK J. MAFERA, OF REVERE, MASSACHUSETTS

METHOD OF FORMING WIRE FENCE FABRIC

Application filed September 3, 1930. Serial No. 479,475.

This invention relates to woven wire fence such as is commonly used for fencing industrial and residential properties.

The method of manufacturing such fencing leaves at the top or bottom edge, or both, of the fence a selvage in the form of a somewhat ragged and unsightly line of twists or barbs. This results from the fact that the fence is woven of one continuous fabric with-
out a break except at its top and bottom where the strands are twisted upon each other as a selvage and finish.

For industrial properties, such ragged selvages are not objectionable but in the case of fencing for residential properties where the fence is usually fairly low and its appearance not only as a fence but in its relation to the property which it encloses is a vital factor, such unsightly selvages, particu-
larly the upper selvage, is apt to be a decided disadvantage.

The twists or barbs are not particularly artistic or ornamental and to this extent detract from the harmonious effect of the fence as a whole. Moreover, these twists or barbs, particularly in the upper selvage, constitute projecting elements upon which clothing may catch or hands may become cut, with resultant liability to the property owner.

The object of my present invention is to eliminate each ragged selvage, particularly at the top of the fence, without sacrificing anything of the essential strength and rigidity, of the fence itself, thus to avoid danger of injury to hands or clothing, while at the same time providing a selvage which is at once ornamental and attractive so as to enhance rather than detract from the general artistic appearance of the fence itself and the property which it encloses, all in a fence construction which may be manufactured and erected without departing from accepted methods now followed.

This object, together with certain features of advantage which will appear more fully hereinafter, is secured in the fence constituting the subject-matter of the present invention.

As illustrative of the principles involved, I describe and show in the accompanying

specification and drawings a form of fence which I have found highly satisfactory under actual service conditions and one which is well adapted to the requirements of commercial manufacture.

In such drawings:

Fig. 1 is a general view of a section of fence in accordance with my invention, and

Fig. 2 is a fragmentary detail showing my novel selvage.

According to usual practice, my fence is woven of any suitable material, as wire of desired gauge, so as to present a succession of interlocked meshes 1 of any desired size and shape. These constitute a continuous fabric of desired length and height which may be erected as a fence by any usual methods. One of the fence posts is indicated at 2 and a fragment of the top rail at 3 (Fig. 1).

In sharp distinction to the usual woven fence, however, the upper and bottom edges of the fabric or both of them, are closed, rounded, or otherwise given a smooth and attractive configuration instead of being twisted upon each other as a barbed or ragged selvage.

This is indicated somewhat diagrammatically in Fig. 2, wherein the upper terminal ends 4 of opposed strands (see dotted lines) in each mesh at the upper and lower edge of the fabric are brought together as indicated in full lines to close the meshes at such edge and thus avoid leaving any barbed or ragged projections at such edge.

Such terminal ends 4 may be closed upon one another in any suitable manner, as by spot welding or otherwise, forming an integral joint, as indicated at 5 in Fig. 2, which is smooth and rounded and ornamental and attractive.

The upper and/or lower edges of the fence thus present selvages which are devoid of any sharp projections, as barbs or twists which may cut the hands or tear the clothing. Being smooth, rounded and unbroken, they add to rather than detract from the appearance of the fence and the property which it encloses.

Although both top and bottom edges of the fence fabric are shown as continuously

smooth and unbroken, it will be understood that only the top edge need be so fabricated and that the bottom edge may be finished off in the usual twists or barbs if desired.

5 Similarly the fabric pattern itself may be variously formed, with meshes of any desired shape and size, and the terminal ends 4 may be variously brought together and united, as by soldering, welding, crimping, or any other 10 means of joining the same, whether mechanical or electrical.

These and all such modifications may obviously be resorted to within the spirit and scope of my invention as defined by the appended claims.

15 What I therefore claim and desire to secure by Letters Patent is:

1. The method of forming woven wire fencing with a selvage devoid of projections, 20 which consists in bending the terminal end portions of related pairs of the strands of the fencing into alined end-to-end abutting relation, and welding said end portions together.

25 2. The method of forming woven wire fencing with a selvage devoid of projections, which consists in bending and thereby so shaping the terminal end portions of related pairs of strands of the fencing that when said 30 end portions are brought into alined end-to-end abutting relation they form a continuous regular curve, bringing said end portions into alined end-to-end abutting relation, and welding said end portions together.

35 In testimony whereof I affix my signature.
FRANK J. MAFERA.
